UNITED STATES PATENT OFFICE.

JOAQUIN A. LOPEZ, OF BANES, CUBA.

SHOE-CLAMP.

1,178,083.

Specification of Letters Patent.

Patented Apr. 4, 1916.

Application filed April 24, 1915. Serial No. 23,780.

To all whom it may concern:

Be it known that I, JOAQUIN A. LOPEZ, a citizen of the Republic of Cuba, residing at Banes, in the Province of Oriente, Cuba, 5 have invented certain new and useful Improvements in Shoe-Clamps; and I do hereby declare the following to be a full, clear, and exact description of the invention, such as will enable others skilled in the art 10 to which it appertains to make and use the same.

This invention relates to new and useful improvements in shoe holding devices, and is particularly directed to the provision of 15 means associated with the shoe holding member of a polishing stand to engage the shoe, and hold it against movement during the operation of cleaning and polishing it.

It is an object of the present invention to 20 provide such holding means for the shoe engaging members wherein they are efficiently held, and resiliently movable so that a shoe may be readily engaged between and gripped thereby.

25 It is further the object of the invention to provide such a device which is of such simple design that it may be manufactured at a minimum cost consistent with durability and efficiency of operation, and to this

30 end it is more particularly the object to provide such a shoe gripping member which may be stamped from a single sheet of metal.

With the above and other objects and advantages in view, the invention resides more 35 particularly in the novel combination, formation and arrangement of parts more fully hereinafter described and pointed out in the appended claims.

40 Reference is had to the accompanying drawings, wherein similar characters of reference designate corresponding parts throughout the several views and in which,

Figure 1 is a side elevation of the shoe 45 holding member of a boot black stand, and showing the improved shoe gripping means associated therewith. Fig. 2 is a bottom plan view of the structure shown in Fig. 1. Fig. 3 is a transverse sectional view on the 50 line 3—3 of Fig. 1. Fig. 4 is a perspective view of one of the gripping members.

Referring now more particularly to the

accompanying drawings, 5 designates the usual shoe holding plate of a boot black or polishing stand from the sole portion of 55 which depends a lug 6 carrying a transverse bolt 7 which holds the gripping members of the device. Each of these gripping members is formed of a single oblong sheet of metal having one end portion thereof bent 60 laterally at 8 to form a shoe engaging arm. The plate is slotted adjacent its side, and has its body portion bent at right angles to form a substantially horizontal section 9 disposed adjacent the under face of the shoe 65 holding plate, and a vertical section 10 apertured at 11 to slidably receive the holding bolt. Those portions of the plate outwardly of the slots are bent in an opposite direction to form handle sections 12 whereby the gripping members may be readily 70 manipulated. These handle sections also serve as a brace means for the horizontal portions 9, and as a guard for the ends of the bolts. The bolts have their outer ends 75 threaded at 13 and nuts 14 are provided on these ends which adjustably hold expansile springs 15 bearing thereagainst and against the vertical portions 10 of the gripping members to urge these gripping members in- 80 wardly.

From the foregoing it is seen that an exceedingly simple device has been provided which may be associated with the conventional type of boot black stand by merely 85 providing a securing means for the shaft 7. The gripping members are held against turning on the shaft 7 by the engagement of their portions 9 with the bottom face of the shoe holding plate. 90

What is claimed is:

1. The combination with a shoe holding plate of a transverse shaft held spaced below said plate, gripping members each comprising a horizontal portion adjacent the 95 under face of the plate, a shoe engaging arm at the outer end of the portion, a depending portion at the inner end thereof slidably secured on the shaft and springs on the end portion of the shaft urging said gripping members inwardly.

2. The combination with a shoe holding plate of a transverse shaft held spaced therebelow, and gripping members slidably

on the shaft and spring urged inwardly, each of said members being formed of a single plate of metal having one end bent to form a shoe engaging arm and being provided with longitudinal spaced slits, with the portions inwardly of the slits intermediately bent at right angle, and the portions outwardly of said slits intermediately bent

at right angles in an opposite direction to form handle portions. 10

In testimony whereof, I affix my signature, in the presence of two witnesses.

JOAQUIN A. LOPEZ.

Witnesses:

J. L. BETANCOURT,
E. F. ALVAREZ.
